Filed July 2, 1959, Ser. No. 56,643

Term of patent 14 years

(Cl. D83—1)

FIG. 1

FIG. 3

FIG. 4

FIG. 2

FIG. 5

FIG. 1 is a front perspective view of a casing for a baby nursing bottle sterilizer or the like embodying my new design;

FIG. 2 is a front elevational view thereof on a slightly reduced scale;

FIG. 3 is a top plan view thereof on a slightly reduced scale;

FIG. 4 is a right side elevational view thereof on a slightly reduced scale; and

FIG. 5 is a rear elevational view thereof on a slightly reduced scale.

The left side of the sterilizer casing, not shown, is like the right side illustrated in FIG. 4, and the bottom of the casing is plain and unornamented.

I claim:

The ornamental design for a casing for a baby nursing bottle sterilizer or the like, substantially as shown and described.
